UNITED STATES PATENT OFFICE.

MIKE BERG, OF PETTIBONE, NORTH DAKOTA, ASSIGNOR OF ONE-HALF TO IRVIN J. DAHLSTROM, OF PETTIBONE, NORTH DAKOTA.

LOADER.

Application filed November 24, 1922. Serial No. 603,054.

To all whom it may concern:

Be it known that I, MIKE BERG, a citizen of the United States, residing at Pettibone, in the county of Kidder and State of North Dakota, have invented new and useful Improvements in Loaders, of which the following is a specification.

My present invention has reference to a portable loading apparatus.

My improvement is particularly adaptable for use in fields for gathering and elevating materials, such as hay, etc., to arrange the same on vehicles for removal to a storage place or stack, or to arrange the hay in a pile or stack at one side or end of the apparatus.

In carrying out my invention, I propose to provide upon a movable body an upwardly inclined elevator having means, in the nature of a motor thereon for operating the same, said means being also employed for revolving either of a pair of drums, the said drums being free mounted but susceptible for engagement by clutches and the said drums have wound therearound a cable, one strand of which being guided through suitable sheave wheels attached to supports disposed a distance away from the elevator, the said strand being secured to the rear end of a scraper, while the second strand is attached to the front end of the scraper, and whereby the scraper may be caused to move toward the elevator to permit of the load therefrom being deposited on said elevator and thereafter the said scraper may be returned to its initial position for gathering another load.

It is also my aim to produce a loading apparatus of the class described which shall be of a comparatively simple nature, one which may be cheaply manufactured, easily and positively operated and thoroughly reliable and efficient in such operation.

The invention further consists in the construction, combination and operative arrangement of parts, such as is disclosed by the drawings which accompany and which form part of this specification.

In the drawings:

Figure 1 is a side elevation of the improvement, the scraper being arranged in its initial position a considerable distance away from the elevator, and parts of the latter and the movable supporting body therefor being in section.

Figure 2 is a side elevation of the improvement but showing the scraper drawn on to the elevator for depositing its load thereon.

Figure 3 is an enlarged top plan view of the construction as illustrated in Figure 1.

Figure 4 is a plan view of the movable body or truck with the elevator removed therefrom, and parts being in section.

Before proceeding with a detailed description of my improvement, it is to be understood that while the same is primarily devised for use as a farm implement, the same is not to be so restricted in its useful employment, as the loader will be found efficient in any other connection where material is to be gathered by a scraper and arranged upon an elevator which will deposit the same on a conveyance or which will stack the material adjacent to the said elevator.

Referring now to the drawings in detail, the numeral 1 designates a truck. In the present instance, the truck is mounted on wheels 2. When properly arranged in a field or other place for receiving a load on the elevator, supported by the truck and hereinafter to be described, the wheels 2 are blocked to prevent the accidental turning thereof and the consequent movement of the truck.

Suitably supported at an upward inclination on the body of the truck 1 is an elevator 3. The elevator proper is arranged between side boards 4, the elevator being in the nature of an endless belt 5 provided with transverse flights 6, the ends of the belt being arranged around rollers 7 respectively that are keyed or otherwise secured to shafts 8 and 9 respectively. In addition to the shafts 8 and 9 there is another shaft 10 disposed a slight distance above the shaft 9 and arranged between the leads of the elevator. This shaft, as well as the upper shaft 8 have on their ends, sprocket wheels 11 and 12 respectively, and around these sprocket wheels are trained sprocket chains 13 respectively. In addition to the sprockets on the lower shaft 10 there are secured other sprockets 14 respectively, and around these last mentioned sprockets there are trained endless chains 15 respectively which are also trained around sprocket wheels 16 respectively that are secured on a shaft 17 arranged transversely of the frame or body of the truck 1 and journaled in suitable bear-

85

ings 18 respectively. On the shaft 17 there are keyed toothed wheels 19 respectively and meshing with these wheels 19 are pinions 20 respectively secured upon a counter shaft 21 journaled in bearings 22 on the frame or body of the truck 1. The counter shaft has secured thereon a pulley wheel 23 around which is trained an endless belt 24 which is also trained around a pulley 25 on the drive shaft 26 of a motor 27 which latter is suitably supported on the frame or body of the truck 1. It will thus be apparent that when the motor is in action the counter shaft will be turned which will impart motion to the main shaft 17 and the latter through the medium of the sprocket chains connected to the sprockets on the shaft 10 will operate the sprocket chains 13 to cause the operation of the elevator. The shaft of the motor turns only in one direction, so that the upper lead of the elevator always travels in an upward direction.

Between the side boards, at the receiving end of the elevator there is a downwardly inclined lip board 28 on which the scraper, hereinafter to be described will travel, and on the lip board there is a contact strip 29 against which the inner or forward end of the scraper will contact to permit of the tilting of the scraper by means presently to be described and to deliver the load therefrom on to the elevator. The load thus received will, of course, be raised to the rear of the truck 1 and be delivered through a suitable chute 30 to a wagon or like conveyance arranged below the truck. If desired, the load may be arranged in a pile or stack at the rear of the truck.

Freely mounted on the main shaft 17, outward of the sprocket wheels 18, and consequently outward with respect to the sides of the truck, there are drums 31 and 32 respectively. On the outer side or face of each drum there is a clutch surface 33 and 34 respectively. The outer ends of the shaft 17 are received in and keyed or splined to bearings 35 respectively which are in the nature of tubular members and which have their inner faces provided with clutch surfaces 36 and 37 respectively. The tubular clutches 35 are arranged for revoluble but held against longitudinal movement in members 37 that are pivoted, as at 38 to brackets 39 which extend outwardly from the sides of the truck. The opposite ends of the members 37 are pivoted, as at 40 to a rod or bar 40' which is, of course, arranged transversely with respect to the truck, and the said rod is provided, adjacent to one of its ends with an offset operating handle or lever 41. Secured to and wound around the respective drums 31 and 32 are cables 42 and 43 respectively. The cable 42 is directed around sheave wheels 44 and 45 respectively which are loosely supported by stakes 46 and 47 re-

spectively that are driven into the ground at the place where the load is to be received, such place being disposed a considerable distance away from the truck and elevator. The sheave wheel 44 is in a line with the drum 31, and the sheave wheel 45 is in a line with the longitudinal center of the elevator. The free end of the strand or cable 42 is secured, as at 48 to a bail 49 on the rear end of a scraper 50. The scraper is in the nature of a material gathering element and while the same, in the showing of the drawings is illustrated in the nature of a slideable fork, it is to be understood that if desired the gathering element may be otherwise constructed. The scraper 50 has its sides provided with upwardly extending handles 51 arranged at the rear thereof, while its said sides have also pivotally connected thereto the side or parallel members of a substantially U-shaped bail 52.

At the front of the truck, and straddling the elevator there is a substantially U-shaped frame, broadly indicated by the numeral 53. On this frame, in a line with the transverse center of the drum 32 there is secured a sheave wheel 54, and also on the frame in a line with the longitudinal center of the elevator there is a second sheave wheel 55. The cable 43 is trained around both of these sheave wheels and is directed toward the scraper and secured to the center of the bail 52 thereof.

As previously stated, the strands or cables 42 and 43 are wound around the respective drums 31 and 32, and also, as previously stated, the main shaft 17 revolves always in one direction. Thus by operating the handle 41 to move the rod 40' to bring the clutch element 37 in engagement with the clutch element 34 on the drum 32 the clutch surface 36 will be brought away from the clutch surface 33 on the drum 31, the clutch sleeves, being splined or keyed on the shaft 17. Thus the drum 31 is freed from the shaft, but the drum 32 is locked thereon and will turn to wind the cable 34 thereon. The winding of the cable 34 draws the scraper or gatherer 50 toward the elevator, causing the same to travel over the lip board 28 and to engage with the contact strip 29, a further drawing on the said cable causing the tilting of the gatherer or scraper so that the load therefrom will be deposited on to the elevator. In the meantime the strand or cable 42 is unwound from the drum 31. When the scraper is to be returned for another load, the handle or lever 41 is operated in a reverse direction, causing the clutch surface 36 to engage with the clutch surface 33 on the drum 31 and bringing the clutch surface 37 to engage with the clutch surface 34 on the drum 32. This frees the drum 32 from the shaft but moves the drum 31 thereon and the turning of the said drum 31 will

cause the cable 42 to be wound therearound, and such movement of the cable will, of course, cause the scraper or gatherer to be moved outwardly away from the elevator.

It is believed that the foregoing description, when taken in connection with the drawings will fully set forth the construction, operation and advantages of the improvement to those skilled in the art to 10 which such inventions relate, and it is thought necessary to add that the showing and description refer only to a satisfactory embodiment of the invention as it now appears to me and that I may make such 15 changes therefrom as fall within the scope of what is claimed.

Having described the invention, I claim:—
In a loader, a wheeled support, laterally

disposed brackets extending from a support, bearing members pivotally secured thereto 20 at their outer ends thereof, a shaft transversing the support and mounted for rotation in the bearing members, means for rotating said shaft, a drum mounted for free rotation on each end of the shaft, a clutch 25 member on each drum, a clutch member on each bearing member cooperatively associated with the clutch members of the drums, a bar transversing the support and having its ends pivotally secured to the bearing members, and means for moving said bar transversely for operating the drums as and for the purpose specified.

In testimony whereof I affix my signature.

MIKE BERG.
